RETAINING RING FOR DIAL COVERS
AND THE LIKE

Edward F. Geiger and Reynold B. Johnson, Binghamton, N. Y., assignors to International Business Machines Corporation, New York, N. Y., a corporation of New York

Application July 1, 1946, Serial No. 680,628

7 Claims. (Cl. 58—91)

1

This invention relates to clocks and similar apparatus having dials, or the like, which are covered by transparent members, and more particularly to structures for retaining the transparent cover members in place.

An object of the invention is to provide apparatus of the type referred to which is of improved construction and arrangement of parts.

Another object is to provide a new and improved structure for retaining covers in position which is of relatively low cost and which is neat and attractive in appearance.

A further object is to provide a new and improved composite ring structure for retaining transparent covers for clock dials and the like, in place, which ring structure can be easily and quickly snapped into place from the front of the clock without tools and which is pleasing in appearance.

Other objects of the invention will be pointed out in the following description and claims and illustrated in the accompanying drawings which disclose by way of example, the principle of the invention and the best mode, which has been contemplated, of applying that principle.

In the drawings:

Fig. 1 is a front elevation showing the present invention as embodied in a clock.

Fig. 2 is a transverse vertical section taken on the line 2—2 of Fig. 1.

Fig. 3 is a detail view showing an improved form of composite retaining ring structure as assembled and prior to its being mounted in the clock.

Fig. 4 is a fragmentary assembly view of the top part of the composite ring structure as it appears in Fig. 3, the view being on an enlarged scale so as to illustrate more clearly the detailed structure of the ring.

Fig. 5 is an enlarged fragmentary assembly view like Fig. 4 and showing the bottom part of the composite ring as it appears in Fig. 3.

Fig. 6 is a detail view showing the split ring which forms the solid core of the composite ring structure of Fig. 3.

Referring now in detail to the construction illustrated and first to Figs. 1 and 2, the reference numeral 10 indicates the improved clock structure in its entirety. The clock 10 comprises a one piece metal casing 11 formed in any suitable manner such, for example, as by a spinning operation. The casing 11 is so formed as to provide a centrally disposed disk or backing plate 12 surrounded by a peripheral skirt portion 13, the latter terminating forwardly of the disk 12.

2

in a ring-shaped flange 14 which is spaced forwardly from the annular periphery of the disk 12 to provide an annular groove 15 therebetween. A clock dial 16 is centrally mounted on the front of the disk 12; and, on the back of the disk is fixed a mounting plate 17 provided with a rearwardly extending hook member 18 for the purpose of mounting the clock on the wall, or the like. The conventional operating mechanism for the clock is mounted within a housing 19 suitably secured on the rear of the mounting plate 17. The minutes arbor 20 and hours sleeve 21 surrounding the arbor 20, extend forwardly through centrally located and aligned openings in the housing 19, plate 17, and disk 12. The minutes hand 22 is suitably attached to the forward end of the arbor 20 and the hours hand 23 on the sleeve.

A transparent cover member 25 encloses the space occupied by the hands 22 and 23 and is secured at its annular periphery against the disk 12 by a composite retaining ring structure 30, the latter being disposed between the periphery of the cover member 25 and the flange 14. As is conventional, the cover member 25 is made of glass and is suitably formed as a segment of a sphere. The diameter of the annular periphery of the cover member is slightly less than the inside diameter of the circular flange 14 so that the cover 25 can pass through the circular opening defined by the flange when mounting and removing the cover from the front.

As will presently appear, the composite ring structure 30 when first assembled and prior to its being installed in position in the clock, is of a larger diameter than the inside diameter of the flange 14. The ring structure 30 is resiliently contractible in a circumferential direction, so that it can be manually contracted to permit its being inserted past the flange 14. After passing the flange 14, the ring structure 30 will expand and thereby engage the inner surface of the flange 14 and the periphery of the cover 25 so as to firmly hold the latter in position against the disk 12.

45 The composite ring structure 30 is shown in Fig. 3 as it is first assembled and before mounting in place in the clock structure. The details of construction of the ring 30 are shown more clearly in Figs. 4, 5, and 6. As shown, the ring structure 30 comprises generally a solid core element 31, a first relatively long tubular section 32, and a second relatively short tubular section 33. The core element 31 is shown in Fig. 6 as being preferably made from selected wire stock

and as being in the form of a split metal ring having a pair of ends 34 and 35, respectively, which are spaced from one another when the element 31 is assembled with the tubular sections 32 and 33, for the purpose of permitting circumferential expansion and contraction. The relatively long tubular section 32 is shown more clearly in Fig. 5 as being formed by helically winding a length of selected steel wire stock about an imaginary longitudinal axis to provide a longitudinal central bore which receives the core element 31. The adjacent convolutions of the helically wound section 32 abut one another. The relatively short tubular section 33 is shown more clearly in Fig. 4 and is also formed by helically winding a length of selected steel wire stock about an imaginary longitudinal axis to provide a central bore receiving the core element 31. The adjacent convolutions of the helically wound tubular section 33 are spaced from one another so as to provide for circumferential contraction of the section 33 when a suitable force is applied. The inherent resiliency of the steel wire stock from which the section 33 is formed assures the expansion of the section back to its normal length upon removal of the applied force. It will be noted that the diameters of the convolutions of both tubular sections are approximately the same.

As stated, the component parts of the complete retaining ring structure are shown in Figs. 3, 4, and 5 in their normal assembled relation and without a contracting force being applied. In order to assemble the parts in the manner shown, the closely wound tubular section 32 is first threaded on one end of the core element 31 for about one half the length of the section 32. Then the relatively short section 33 is threaded on the other end of the core element 31 and moved around until its leading end abuts the inserted end of the section 32. The other or free end of the section 32 is then threaded on said other end of the core element 31 and until it abuts the other end of the section 33. With the two sections 32 and 33 thus assembled on the core element 31 and the ends thereof in abutting relation, the two ends 34 and 35 of the core element are separated a predetermined distance (see Figs. 3 and 5). This gap between the two ends 34 and 35 represents the designed maximum amount of circumferential contraction provided by the particular composite ring structure forming a part of the disclosed embodiment. It is noted that in the assembled relation, the gap between the two ends 34 and 35 of the core element is bridged by the tubular section 32, and the tubular section 33 is located diametrically opposite such gap.

As stated hereinabove, when it is desired to install the transparent cover member 25 and composite ring structure 30 as a part of the clock, the cover 25 is first placed in a central position on the disk 12 where it covers the dial 16 and hands 22 and 23 and the composite ring structure is then manually contracted so as to pass the circular flange 14 and moved into position behind the flange 14 where it expands due to its inherent resiliency to engage and hold the cover 25 tightly against the disk 12.

From the foregoing it will be apparent that the composite retaining ring structure 30 in conjunction with the backing plate or disk 12 and the annular flange 14, provide a simple, inexpensive, and effective structure for mounting and demounting the conventional glass cover from the front of a clock. Because of the fact that

both tubular sections 32 and 33 are formed of helically wound wire stock and the diameters of the convolutions thereof are approximately the same value the retaining ring structure appears from the front as an ornamental molding or bead which is pleasing in appearance. The amount of resilient contraction required to pass the annular flange and effectively function as a retaining ring when in place, is relatively small, for example, in a 12-inch clock the maximum circumferential contraction may be on the order of .28 of an inch. Consequently, the spaces between adjacent convolutions of the sections are relatively small when installed and the difference between the two sections will not be apparent to the eye of the casual observer. Because the ring and glass can be mounted from the front of the clock, and because of the simple construction of the ring, the cost is considerably less than in prior structure of this type where the glass is usually mounted from the back in order to overcome the unsightly appearance of conventional snap rings. Ready access to the hands and dial of the clock is provided without requiring the removal or disturbing of the clock movement. Furthermore, as the tubular casing surrounding the core of the snap rings is formed from helically wound wire stock, the ring structure easily adjusts itself to unevenness of fit and consequently can be used with a relatively wide variation in fit of glass to case. Also, the glass can be quickly mounted and demounted without requiring the use of tools.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

45 What is claimed is:

1. A composite retaining ring structure comprising a ring-shaped core having a pair of separated ends to provide circumferential contraction and expansion thereof; and ring-shaped tubular means surrounding said core and divided circumferentially into a first section bridging the separated ends of the core and being relatively non-contractile yet expansible circumferentially of the core and a second section filling the space between the ends of the first section and being resiliently contractile and expansible circumferentially of the core.

2. A composite retaining ring structure comprising a split ring element formed of wire stock with the two ends thereof separated to provide a gap therebetween for permitting circumferential expansion and contraction; a tubular element having a longitudinal central bore receiving said ring element and having a pair of ends spaced from one another to provide a gap therebetween, and being positioned on said ring element so that the two gaps are spaced circumferentially from one another; and a helically wound compression spring member formed of resilient wire stock and having a central bore receiving said ring element and filling the gap between the two ends of the tubular element.

3. A ring structure as set forth in claim 2 75 wherein the diameter of the convolutions of the

helical spring member is approximately the same as that of the tubular element.

4. A ring structure as set forth in claim 2 wherein the tubular element comprises wire stock helically wound about an imaginary longitudinal axis to provide the central bore and with adjacent convolutions abutting one another.

5. A ring structure as set forth in claim 2 wherein the tubular element comprises wire stock helically wound about an imaginary longitudinal axis to provide the central bore and with adjacent convolutions abutting one another, and wherein the diameter of the several convolutions of the tubular element and of the helical spring member is approximately the same.

6. A composite retaining ring structure comprising a solid core member formed as a split ring with the two ends thereof separated to provide a gap therebetween to permit expansion and contraction; a tubular member having a central bore receiving said core and bridging said gap and having a pair of ends spaced from one another to provide a gap therebetween circumferentially spaced from said first named gap; said tubular member comprising solid stock helically wound about an imaginary longitudinal axis to provide the central bore and with its adjacent convolutions abutting one another; and a helically wound compression spring member having a central bore receiving said core member and filling the gap between the ends of said tubular member.

7. A composite retaining ring structure for

clocks and the like comprising a ring-shaped core element having a pair of separated ends providing a gap therebetween for permitting circumferential expansion and contraction thereof; a ring-shaped tube having a central bore receiving said core element and having a pair of ends separated from one another to provide a gap therebetween and the tube being positioned on the core element so that the two gaps are spaced circumferentially from one another; and a separate tubular member having a bore receiving said core and filling the gap between the two ends of said ring-shaped tube, said separate tubular member being in the form of a helically wound compression spring member and having a cross-sectional diameter approximately the same as said tube and being so constructed as to provide for circumferential contraction and expansion.
